UNITED STATES PATENT OFFICE.

ROBERT SANFORD RILEY, OF WORCESTER, MASSACHUSETTS, ASSIGNOR TO SANFORD-RILEY STOKER CO., LTD., OF WORCESTER, MASSACHUSETTS, A CORPORATION OF MASSACHUSETTS.

AUTOMATIC STOKER.

1,292,649.

Specification of Letters Patent. Patented Jan. 28, 1919.

Application filed July 24, 1917. Serial No. 182,545.

To all whom it may concern:

Be it known that I, ROBERT SANFORD RILEY, a citizen of the United States, residing at Worcester, in the county of Worcester 5 and State of Massachusetts, have invented new and useful Improvements in Automatic Stokers, of which the following is a specification.

The present invention relates to furnaces especially adapted for steam boilers, of the type in which fuel is automatically fed and is continuously propelled, while burning, from the admission point to a discharge point at which the incombustible residue of 15 refuse is discharged to an ash pit. More particularly the invention is preferably applied to a stoker of the underfeed type, which is distinguished by a construction and arrangement of means comprising one 20 or a plurality of fuel channels or retorts into which the green fuel is admitted, and air discharging or supplying members arranged to deliver air for the support of combustion above the incoming green fuel, 25 in a zone through which such fuel must pass before reaching the fuel bed and becoming fully ignited.

The object of the invention is primarily to provide additional grate area on which 30 the fuel is burned after it emerges from the retorts. This additional grate area is provided at each side of each retort of the furnace; and it allows the coked and partly burned fuel to be pushed out from the retorts more rapidly than is possible with furnaces of the types heretofore constructed, and then to be burned more rapidly by reason of the additional quantity of air supplied through the more extended grate area; 40 thus developing more heat and increasing the power of the boiler under which the furnace is placed.

In the present specification I have shown and described the application of the invention to an underfeed stoker or furnace of the type in which parallel bars arranged in pairs on a downward and rearward slant, spaced apart and carrying perforated grate blocks or equivalent air emission members, 45 define the retorts, in connection with bottom plates between the bars of each pair, and in which the grate blocks extend laterally away from the retorts over a space or spaces wherein air under pressure is confined, substantially in the manner fully set forth in

my prior Patent No. 1,090,651; and for the purpose of illustration, but not of indicating any limitation in the scope or use of the invention, have depicted in the drawings a furnace having three retorts. The novel 60 features of the invention are herein shown as embodied in additional bars parallel with the retort side bars between adjacent retorts and at the outer sides of the outermost retorts; in other words, at each side, or on both sides, 65 of each retort. Grate blocks are mounted on said additional bars in a manner such as to form grate connections in continuation of the fuel supporting surfaces or grate sections made by the grate blocks which are 70 mounted on the retort side bars. Three forms or modifications of the invention are illustrated; in one of which the retort sides are moved back and forth to propel the fuel from admission points at the forward end 75 of the furnace to a discharge point at the rear, while the additional grate sections are stationary in order to disintegrate the burning fuel; in the second of which the retort sides are stationary and the additional grate 80 sections are movable back and forth, for the same purpose; and in the third of which the retort sides and additional grate sections are all movable.

In the drawings, Figure 1 is a longitudinal vertical section of a stoker illustrating the first modification above described on line 1-1 of Figs. 2 and 3.

Fig. 2 is a plan view of the stoker, one of the retorts being shown in section on line 90 2-2 of Fig. 1.

Fig. 3 is a cross section of two of the retorts and the intermediate stationary grate element on line 3-3 of Fig. 1.

Fig. 4 is a view similar to Fig. 1 of the 95 second modification described on line 4-4 of Figs. 5 and 6.

Fig. 5 is a plan view of the same partly in section on line 5-5 of Fig. 4.

Fig. 6 is a cross section on line 6-6 of 100 Fig. 4.

Fig. 7 is a view similar to Figs. 1 and 4 of the third modification described on line 7-7 of Figs. 8 and 9.

Fig. 8 is a plan view partly in section on 105 line 8-8 of Fig. 7.

Fig. 9 is a cross section on line 9-9 of Fig. 7.

The same reference characters indicate the same parts in all the figures. 110

I will first describe the particular constructions here shown and then point out the principles, use, and advantage of the invention. In general the stoker as shown in 5 Figs. 1, 2, and 3 is the same as in my patent above referred to except that the distance between centers of the retorts has been increased to provide room for the stationary auxiliary grate elements, and other parts of 10 it correspondingly widened. The retort side bars 11, grate blocks 13 or air emission members, carried thereby, stationary retort bottoms 14, overfeed or extension grate blocks 15, 16 and pushers 17 connected to 15 the side bars 11 at the rear of the furnace, refuse supporting dump plates 18 and the rack bars 19 for supporting the same, means for withdrawing said rack bars; and means for feeding fuel into the furnace and propelling it therethrough, consisting of the rams or pushers 20 driven in line with the retorts in guides 21 by a crank shaft 22 and connecting rods 23, are all the same as shown in my patent above named. So also are the 20 hopper 24 for guiding fuel into the guideways 21, and the means for transmitting motion from the plunger to the movable retort walls, which consist of pins 25 extending from the pusher and engageable 25 with abutments 26 and 27 on bars 28 which are connected with the respective side walls. By this means each side bar of each retort is moved back and forth, and the extent of its movement may be varied by placing a 30 greater or less number of filler pieces 29 on a part of the bar 28 of reduced diameter between the abutment 27 and the pin 25.

The fuel is fed into the furnace by the rams or pushers 20, is advanced through the 35 furnace from the admission point to the discharge point 30 by the action of the side walls, and is caused to emerge from the retorts and to spread over the lateral grate blocks or air emission members 13 partly 40 by the rams and partly by the action of the moving retort sides, which extend on a downward inclination toward the rear. In this specification the retort sides are considered to be composed in part of the side bars 45 11 and in part of the grate blocks 13 which are mounted on and carried by said bars. These grate blocks are preferably constructed substantially as shown in my Patent No. 1,090,651, and have openings arranged to 50 discharge air, which is forced under pressure into the space beneath the furnace and flows to the grate blocks through the spaces between adjacent retorts, issuing from said blocks both laterally across retorts and rearwardly. These blocks are also provided 55 with ribs, as shown, which support the fuel and provide intermediate channels through which the air may flow. The overfeed or extension grate blocks 15 and 16 and the 60 pushers 17 are below the level of the retort 65 bottoms 14 and are of such width that they cross the space of each retort between the side walls thereof as shown in Fig. 2, whereby the fuel which passes horizontally out of the rear ends of the retorts flows over the 70 same and is supplied with air to support its combustion by air flowing through channels provided in said grate blocks. The pushers 17 reciprocate with the side walls of the retorts back and forth to a limited extent over 75 the refuse support and propel the refuse to the discharge opening 30 between the rear end of the horizontal part of said support and the adjacent wall 31 of the furnace.

The additional or supplemental grates or 80 grate sections between adjacent retorts, and between the outer retorts and the stationary side walls of the furnace inclosure, which in this embodiment of the invention are stationary, are preferably composed each of a series of grate blocks 32 (see Fig. 3) substantially like the grate blocks 13, which are supported upon a bar or beam 33 substantially like the side bars 11 of the retorts, arranged parallel thereto and mounted in 85 substantially the same way, except that it is stationary. One of these stationary bars is shown in side elevation in Fig. 1, and two of them are shown partly in section in Fig. 2. Their forward ends are provided with 90 flanges 34 which are bolted to flanges 35 on the pusher guides 21. The grate blocks 32 have webs 36 which rest on the upper edge of the bar 33 and are provided with lips 37 through which bolts 38 pass to secure 95 them to the bar, the latter having flanges 39 at its lower edge with which said bolts are engaged. Laterally projecting brackets 40 are provided at intervals on the bar and these brackets support the side webs of 100 certain of the grate blocks so as to prevent said blocks from tilting. These blocks are so formed as to overlap one another in series and thus the blocks which are supported against tilting by the brackets similarly 105 support other blocks which are not engaged with brackets. These blocks 32 have ribs and intermediate channels which respectively support fuel and permit air to flow from the air space beneath the furnace into the 110 fuel thus supported. For illustration in greater detail of the preferred construction of the grate blocks 32, as well as of the grate blocks 13, attention is directed to my prior Patent No. 1,090,651, wherein corresponding blocks are illustrated. The blocks 115 13 here shown are substantially like the blocks illustrated in said patent, while the only material difference in the blocks 32 is that they need not be provided with lateral 120 openings such as are provided in the blocks 13, and in those shown in my patent aforesaid, which discharge air into or across the retorts.

It is to be understood, however, that I do 130

not restrict the invention to any precise character of grate and that the grate blocks which I have shown are merely illustrative of this part of the invention, and are also 5 the form of grate which I prefer to use. Any other construction of grate which is capable of being applied, with or without modification, for the purpose of the additional grates heretofore described may however be used as well as the specific grates 10 here shown.

In the second modification shown in Figs. 4, 5, and 6 the side bars 11 of the several retorts are stationary, being provided with 15 flanges 41 on their forward ends which are secured by bolts 42 to the pusher guides 21, in the manner similar to that in which the bars 33 supporting the grate blocks of the supplemental grate sections are fixed in the 20 modification first described. The supplemental grate sections, however, are movable back and forth horizontally, and for that purpose each of the bars 33 is secured at its forward end to a slide 43 which passes 25 through a guide 44 on the forward end of the furnace structure and is joined by a wrist pin 45 to a rod 46 extending from an eccentric strap 47 which surrounds an eccentric 48 on the drive shaft 22. Preferably 30 provision is made for varying and regulating the extent of motion given to the bars 33. Any means suitable for this purpose may be used, and I have shown for the purpose of illustration one such means 35 which is essentially similar to the variable lost motion regulating means previously described in connection with the movable side walls of the modification first described. Such means comprises a fork 49 on the connecting rod 46 which embraces the end of 40 the slide 43 and carries the wrist pin 45, the latter extending through a slot 50 in that part of the slide which is embraced by the fork and having lost motion therein. A shoulder 51 is provided on the slide as 45 an abutment for filler pieces 52, similar to the filler pieces 29, which are adapted to be placed over the slide 43 between said shoulder and the fork. Connection 50 between the grate supporting bar 33 and the slide 43 is made by a bolt 53 passing through the rear end of the slide and also through an eye 54 secured to the forward end of the bar. All of the movable supplemental grate supporting bars and 55 their operating means in the entire furnace are alike and the foregoing description applies to them all.

The third modification shown in Figs. 7, 8, and 9 combines the elements of the two 60 forms or modifications already described; having movable retort sides and means for reciprocating them as shown in Figs. 1, 2, and 3, and also having movable supplemental grate sections and means for reciprocating the same as shown in Figs. 5, 6,

and 7. It is a part of my invention as embodied in the third form to arrange the driving means for the retort walls and the supplemental grate sections in a manner such that the adjacent grate sections move 70 otherwise than in exact unison; that is, either oppositely to one another or in such wise that one of such sections moves either faster or slower than the adjacent section. The term "grate section" here used includes both the grates which border the 75 retorts and the supplemental or additional grates.

Each of these grate sections is a narrow 80 strip or zone of the entire grate area running from front to rear. This definition is true as to each one of the forms, modifications, or embodiments of the invention described, and in each form there is a relative movement between the sections which 85 adjoin and define the retorts and the sections adjacent thereto.

With the foregoing detailed explanation in mind, it will be understood that the relative reciprocation or vibration between the 90 retort sides, with the grate sections supported thereby, and the supplementary grate sections causes a shearing or separation between the bodies of fuel supported respectively by the several grate sections. 95 That is, between adjacent retorts the fuel is divided or agitated in the operation of the stoker on two shearing lines instead of on one line, as in my previous types of stoker. The relative motion between these 100 bodies of fuel causes the masses of fuel to be broken up and prevents the fuel from fusing together in large lumps and particularly prevents the formation of large masses of clinker.

The supplemental or additional grates or grate sections furnish additional areas on which ignited fuel may be burned and thoroughly supplied with air. In other words, they increase the proportion of the 105 furnace area which supports and supplies air to the burning fuel. This is an advantage inasmuch as those portions of the fuel bed which extend over the retorts cannot be so well and completely supplied with air as are those portions of the bed which 110 rest on grates. Thus an increase in the ratio of grate area to retort area causes increased efficiency in the combustion of fuel, enabling the fuel to be more rapidly burned with generation of more heat, and 115 with more complete combustion of the fuel. The additional grate area between and beside the retorts makes it possible to feed fuel into the furnace more rapidly than heretofore and permits the partly burned 120 fuel to be expelled from the retorts and spread out over the supporting grates more rapidly. At the same time the coking of the fuel in the retorts and combustion of the volatile elements of the fuel take place 125 130

as in my previous types of stoker, so that, by the time the fuel emerges from the retorts, the volatile smoke-producing constituents have been driven off and burned, and 5 the fuel which is deposited on the grates consists practically wholly of coke.

At the same time the grate sections are so narrow that the fuel supported by each stationary section is affected by that which is 10 carried by the adjacent moving section, so that it is stirred up and gradually propelled toward the discharge point as it becomes consumed. Thus the stationary grate sections do not accumulate a stationary body of 15 burned-out fuel refuse, but are constantly supplied with fresh ignited fuel which is constantly fed along as it becomes consumed.

Preferably the grate blocks, carried by the 20 retort side bars, are mounted with some free- dom for lateral movement whereby they are pressed against the supplemental grate blocks by the pressure of fuel in the retorts and thus sifting of the fuel between the adjacent sets of grate blocks is prevented. Sift- 25 ing of fuel between the stationary retort bottoms and the moving side bars of the retorts may be prevented by means substantially the same as shown in my pending applica- 30 tion Serial No. 638,282, filed May 13, 1914, while sifting through the grates themselves is prevented by the construction of the grate blocks, which have transverse webs overlying all openings to the air space or spaces 35 beneath, as set forth in my Patent No. 1,090,651.

The invention which I claim herein com- 40 prises the combination with an underfeed stoker, comprising one or more retorts hav- ing means for causing underfeed combus- 45 tion, and fuel supporting grate sections at each side of the retort, of additional or sup- plemental grate sections adjoining the other grate sections, and means for causing a rela- 50 tive movement between said sections in such manner as to propel and also to shear and disintegrate the fuel. The invention is the same whether embodied in a furnace having only one retort or in a furnace having a plu- 55 rality or multiplicity of retorts; and it is also the same invention whether the relative movement between adjacent grate sections 60 is accomplished in either of the three ways hereinbefore described, or otherwise, and by whatever means or mechanism. Except as 65 last stated, and as stated in the claims, I do not limit the invention; and in particular I would say that the reference to my prior patent is not intended, nor is it to be under- 70 stood, as a restriction of this invention to a 60 furnace or stoker specifically like the one shown in said patent, but as said stoker is the one to which I prefer to apply this invention, the patent has been referred to in amplification of the description of the par-

ticular embodiments of the invention herein 65 shown.

What I claim and desire to secure by Let- 70 ters Patent is:

1. A furnace comprising a fuel feeding re- 75 tort with grate sections flanking and defin- ing the mouth of said retort, means for in- troducing fuel into one end of the retort, the furnace having an outlet for discharge of refuse beyond the retort, supplemental 80 grate sections on the outer sides of the first named sections, and means for moving cer- 85 tain of said sections in such manner back and forth across the plane of the grate as to propel the fuel toward said outlet, with rel- 90 ative motion between contiguous sections. 80

2. A furnace comprising a fuel feeding re- 95 tort with grate sections flanking and defin- ing the mouth of said retort, means for in- troducing fuel into one end of the retort, the furnace having an outlet for discharge 90 of refuse beyond the retort, supplemental grate sections on the outer sides of the first named sections all of said grate sections be- 95 ing inclined and extending from a level above the fuel admission point to a level below the retort bottom at their ends which are nearest to said outlet, and means for moving certain of said sections in such man- 100 ner back and forth across the plane of the grate as to propel the fuel toward said out- 105 let, with relative motion between contiguous sections. 95

3. A furnace comprising a fuel feeding re- 100 tort with grate sections flanking and defin- ing the mouth of said retort, means for in- troducing fuel into one end of the retort, the furnace having an outlet for discharge 105 of refuse beyond the retort, supplemental grate sections on the outer sides of the first named sections, and means for moving cer- 110 tain of said sections back and forth toward and away from said outlet in such manner back and forth across the plane of the grate as to propel the fuel toward said outlet, with relative motion between contiguous sections. 110

4. A furnace comprising a fuel feeding re- 115 tort with grate sections flanking and defin- ing the mouth of said retort, means for in- troducing fuel into one end of the retort, the furnace having an outlet for discharge 120 of refuse beyond the retort, supplemental grate sections on the outer sides of the first named sections, all of said grate sections being inclined and extending from a level above the fuel admission point to a level below the retort bottom at their ends which are nearest to said outlet, and means for moving certain of said sections back and 125 forth toward and away from said outlet in such manner back and forth across the plane of the grate as to propel the fuel toward said outlet, with relative motion between contiguous sections. 125

5. A furnace comprising a fuel feeding retort with grate sections flanking and defining the mouth of said retort, means for introducing fuel into one end of the retort, 5 the furnace having an outlet for discharge of refuse beyond the retort, supplemental grate sections on the outer sides of the first named sections, said sections being all constructed to transmit air to the superposed 10 fuel and prevent passage of the fuel through and between them to the space beneath, and means for moving certain of said sections in such manner back and forth across the plane of the grate as to propel the fuel toward said outlet, with relative motion 15 between contiguous sections.
6. An underfeed furnace comprising a plurality of inclined grate sections arranged in pairs, each pair bounding and including a fuel retort and extending across the plane of the retort bottoms, supplemental grate sections between the said pairs of grate sections, means for injecting fuel into said retorts from beneath the highest part of said 20 grate sections and expelling the fuel from the retorts and over upon said grate sections, an outlet for refuse in rear of the lower ends of the grate sections, and means for moving 25
- certain of said sections endwise toward and away from the outlet with relative motion 20 between adjacent sections, to feed fuel and shear the fuel bed.
7. An underfeed furnace comprising a plurality of inclined grate sections arranged in pairs, each pair bounding and including a fuel retort and extending across the plane of the retort bottoms, supplemental grate sections between the said pairs of grate sections, means for injecting fuel into said retorts from beneath the highest part of said 35 grate sections and expelling the fuel from the retorts and over upon said grate sections, an outlet for refuse in rear of the lower ends of the grate sections, and means for moving 40 certain of said sections endwise toward and away from the outlet with relative motion 45 between adjacent sections, to feed fuel and shear the fuel bed, other sections being held stationary and being of such narrow width that the fuel upon them is moved in the feeding direction by the fuel carried in the same direction by the moving sections.

In testimony whereof I have affixed my signature.

ROBERT SANFORD RILEY.
